US0D1050312S

(12) **United States Design Patent** (10) **Patent No.:** **US D1,050,312 S**
(45) **Date of Patent:** **** Nov. 5, 2024**

(54) **PICKLEBALL PADDLE**

(71) Applicant: **Six Zero Pickleball PTY LTD**, Moffat Beach (AU)
(72) Inventor: **Dale Young**, Moffat Beach (AU)
(73) Assignee: **Six Zero Pickleball PTY LTD**, Moffat Beach (AU)

(**) Term: **15 Years**

(21) Appl. No.: **29/886,546**

(22) Filed: **Mar. 9, 2023**

(51) **LOC (14) Cl.** **21-02**
(52) **U.S. Cl.**

USPC **D21/731**
